SHIP CONSTRUCTION

John M. Sponsler, Birmingham, Ala.

Application August 11, 1937, Serial No. 158,482

1 Claim. (Cl. 114—0.5)

My invention relates to ship construction and has for an object the provision of a construction adapted to permit the salvaging of articles of value, such as jewelry, money, etc., from the strong room of sunken vessels.

It is a further object of my invention to provide a ship construction embodying a strong room for the storage of articles of great value, and designed to permit the use of a diving bell for salvaging the articles from the strong room.

It is a further object of my invention to provide a plurality of passageways leading from the top and sides of a vessel to the strong room and providing two or more closures for each passageway. By providing several passageways leading to the strong room, the salvaging crew may choose the most accessible way. It is also desirable to have more than one passageway leading to the strong room as one of same may become damaged due to a collision of vessels, or for some other reason, rendered useless.

My invention embodies other novel features, details of construction and arrangement of parts which are hereinafter set forth in the specification and claim and illustrated in the accompanying drawing, forming part thereof, wherein:

The single figure in the drawing is a fragmentary view in transverse section showing the construction and arrangement of passageways leading to a strong room located in a vessel, and also showing the manner in which a diving bell may be secured to the ship for transferring valuables from the strong room to the diving bell.

Referring now to the drawing for a better understanding of my invention, I show the sides 5 and 6 and the deck 7 of a vessel having a strong room 8 located therein. The sides and deck of the vessel are provided with openings 9 having sleeves 10 secured therein. The sleeves are welded to the ship, or otherwise secured thereto, and have flanges 11 provided at their outer ends to receive the covers 12. These covers may be secured to their respective flanges by means of bolts 13. Water tight passageways 14 extend from the openings 9 to the openings 16 formed in the shell of the strong room and are welded in position to the ship hull at 17 and to the strong room shell at 18.

Suitable water tight closures 19 are provided for the strong room to close the opening 16 and may, if desired, be provided with suitable locking means, such as a combination lock, the knob of which is indicated at 21.

I show a portion of a diving bell 25 having an outer wall 26 provided with an opening 27. A cover 28 is secured in position to cover the opening

by means of screws 29. A circular flange 31 projects outwardly from the wall of the diving bell, and incircling the opening 27, for engagement with the face of the flange 11. In order to provide a water tight seat, the outer edge of the flange 31 may be provided with a facing 32 consisting of relatively soft metal, such as lead. A plurality of clamping members 33 are provided with off-set portions 34 at their outer ends for engagement with the back side of flanges 11. The clamping members are mounted in openings 36 formed in the wall 26 and are threaded at 37 to receive adjustment nuts 38. The inner ends of the clamping members are provided with square heads 39 for moving the off-set portions 34 into clamping position with the flange 11. Stuffing boxes 41 are provided to prevent leakage around the clamping members.

In salvaging articles of value from sunken vessels embodying my improved construction, the diving bell 25 is lowered for engagement with one of the flanges 11 and secured thereto by means of the clamping members 33. After a water-tight connection has been effected between the ring 31 and the flange 11, the operators within the diving bell then remove the screws 29 and the cover 28 to provide access to the cover 12. The cover 12 is then removed to permit one of the men to move through the passageway 14 and unlock the strong room door 19. In the event the passageway selected for entrance to the strong room has for any reason become flooded with water, the cover 12 of that passageway is sealed against the flange 11 and the cover 28 is replaced in position to cover the opening 27 in the diving bell. The clamping members 33 are then released and the diving bell is moved into position to effect an entrance through one of the other passageways. It will thus be seen that a vessel provided with the strong room and passageway construction herein set forth permits a ready removal of valuables contained within the strong room in the event that the vessel should sink, and that the provision of two or more passageways leading to the strong room permits the diving bell to be readily positioned for entrance of the men through one or more of the passageways.

While I have shown my invention in but one form it is obvious to those skilled in the art that it is not so limited but is susceptible of various changes and modifications without departing from the spirit thereof, and I desire, therefore, that only such limitations shall be placed thereupon as are imposed by the prior art.

I claim:

The combination with a ship having a hull and deck, of a water-tight safe disposed in spaced relation to the hull and deck of the ship and having a plurality of openings formed therein, safe
5 doors provided with locks operable from the outside of the safe and having a water-tight contact with their respective openings, means defining openings located on opposite sides of the hull of the ship, water-tight closure members for
10 said hull openings, means accessible from the out-

side of the hull of the ship for removing said closure members from said hull openings, means defining a water-tight passageway connecting each safe opening with its respective hull opening to provide several independent means of access from the outside of the hull of the ship to the interior of the safe, and means provided at each hull opening for a water-tight attachment of a diving bell. 5

JOHN M. SPONSLER. 10
